[57]

ABSTRACT

A portable electric dryer for athletic equipment, especially for leather equipment, which may be utilized along the side lines of athletic fields, such as a football field, for drying wet balls and other equipment. The dryer includes a mobile cabinet containing a revolving cage of open work material for receiving the balls or other athletic equipment to be dried, and which is located between electrically energized heating elements for drying the balls or equipment as they tumble within the revolving cage.

SHEET 2 OF 2

DRYER FOR ATHLETIC EQUIPMENT

SUMMARY

It is a primary object of the present invention to provide an athletic equipment dryer which may be moved along the side lines of an athletic field and kept in close proximity to the location of play, for receiving and drying balls in inclement weather to not only remove moisture from the surface of wet balls, but to dry the balls by removing the moisture therefrom, so that when a ball is returned to play it will be of a proper weight as specified by the regulations of the game, rather than of an excessive weight due to its moisture content, as where the surface of the ball has merely been wiped with a towel.

Another object of the invention is to provide a dryer capable of drying the ball or other athletic equipment in such a manner that the leather will be soft and pliable rather than stiff and hard after drying.

A further object of the invention is to provide a dryer including a revolving enclosure of open work construction for supporting the balls or equipment to be dried and which is disposed between a plurality of heating elements for drying the balls and equipment as such articles tumble within the enclosure.

Another object of the invention is to provide means to facilitate loading and unloading the enclosure from opposite ends thereof to enable the driest balls or equipment to be initially unloaded.

Various other objects and advantages of the invention will hereinafter become more fully apparent from the following description of the drawings, illustrating a presently preferred embodiment thereof, and wherein:

BRIEF DESCRIPTION OF THE DRAWINGS

FIG. 1 is a perspective view of the dryer;
FIG. 2 is a longitudinal sectional view taken substantially along a plane as indicated by the line 2—2 of FIG. 3, and on an enlarged scale relative to FIG. 1;

FIG. 3 is a cross sectional view taken substantially along a plane as indicated by the line 3—3 of FIG. 2, and showing an access door in a partially open position, and

FIG. 4 is an end elevational view taken substantially along a plane as indicated by the line 4—4 of FIG. 2, and showing the same door in a fully open position.

DESCRIPTION OF THE PREFERRED EMBODIMENT

Referring more specifically to the drawings, the dryer for athletic equipment in its entirety is designated generally 5 and includes a cabinet 6 supported by two rear wheels 7 and a front wheel 8.

As best seen in FIGS. 2 and 3, the cabinet 6 includes a frame 9 preferably composed of angle iron and which is covered with sheet metal 10 to provide a bottom 11, top wall 12, front wall 13, rear wall 14, bottom side wall portions 15 and 16, and upper side wall portions 17 and 18. The upper side wall portions 17 and 18 slope upwardly and inwardly, relative to one another, to the top wall 12. Substantially the entire side wall portion 17 constitutes a door or closure which is swingably connected along its bottom edge to the upper edge of the wall portion 15 by a piano hinge 19. The closure 17 is equipped with a handle 20 and is normally maintained in a closed position by a conventional latch 21, includ-

ing a keeper 22 which is secured to the top wall 12, as seen in FIG. 3.

As seen in FIG. 4, a portion of the lower part of the rear wall 14 is cut out to provide a second access door 23 which is hinged along one side edge thereof, as seen at 24, and which is provided near its other side edge with a handle 25. The door 23 may be provided with a latch, not shown, corresponding to the latch of the door 17. The interior of the cabinet walls, including the doors 17 and 23, are lined with a heat insulating material 26, such as asbestos board.

Pillow blocks 27 and 28 are mounted on and secured to horizontal end portions of the frame 9 which are disposed adjacent to the end walls 13 and 14, respectively, to provide journals for shafts 29 and 30 which are fixed to and project from the ends of an enclosure 31.

The enclosure 31 includes an elongated rectangular rigid frame 32 having corresponding side portions 33 and corresponding end portions 34. The shafts 29 and 30 are welded to and project from said end portions 34, midway of the ends thereof. The enclosure 31 additionally includes a cylindrical cage of open work construction, designated generally 35, which is preferably formed of mesh wire fabric and which includes end walls 36, a cylindrical intermediate portion 37, semi-cylindrical end portions 38 which form extensions of the portion 37, and semi-cylindrical portions 39 and 40, constituting closures. Intermediate portions of the bars 33 are disposed externally of and secured to the intermediate cage portion 37 and to the longitudinal edges of the extensions 38.

Three bosses 41 are fixed to and project outwardly from each bar 33, adjacent the ends and intermediate of the ends thereof, to support a rod 42 which extends substantially from end to end of the cage 35. The closures 39 and 40, adjacent each side edge thereof, are provided with two outwardly projecting apertured ears 43 which are mounted on and slidably engage the rods 42. The closures 39 and 40, when in fully closed positions, as illustrated by the closure 40 in FIG. 2, provide a completely enclosed cylindrical cage. Either closure can be slidably moved and telescoped over the half of the cylindrical cage portion 37, located adjacent thereto, as illustrated by the closure 39, shown in a partly open position in FIG. 2. The closures 39 and 40 are provided with handles 45, located on the sides thereof which face the door 17, when said closures constitute parts of the upper half of the cage 35, as seen in FIGS. 3 and 4.

A mounting bracket 46 is fixed to and projects outwardly from the front wall 13 to provide a support for an electric motor 47 having an output shaft 48 projecting from a gear box 49 of the motor toward the wall 13. The shaft 29 extends through the pillow block 27 and through the front wall 13 and is connected by a coupling 50 to the shaft 48 for revolving the enclosure 31. The shaft 30 terminates in the other pillow block 28.

A plurality, preferably three bars 51 are disposed within and longitudinally of the cabinet 6 and are supported by portions of the frame 9. Each bar or mount 51 supports a plurality of electrical lamp sockets 52 which provide supports for three sets or banks of heat lamps 53, 54 and 55, preferably infra-red lamps, although other types of heat lamps may be utilized. The lamp bulbs 53, 54 and 55 are disposed around and spaced from the enclosure 31 and face toward said enclosure.

As seen in FIG. 3, three conventional electric switches 56, 57 and 58 are mounted on the frame 9, within the cabinet 6, adjacent the door 17. An electric cord 59 connects with each of the switches and extends outwardly of the cabinet 6 and terminates in a conventional plug 60 which may be connected to any conventional extension cord, not shown, leading from a conventional source of electric current. Conductor wires 61 connect the sockets 52 of the heating elements or lamps 53 and 54 to the switch 56 and conductor wires 62 connect the sockets 52 of the lamps 55 to the switch 57. Conductor wires 63, FIG. 1, connect the electric motor 47 to the switch 58.

A tray or pan 64 is mounted in the bottom portion of the cabinet 6 and extends from the front wall 13 to adjacent the rear wall 14. As seen in FIG. 2, the tray or pan slopes downwardly and rearwardly toward the rear wall 13, has open ends, and is lined on its upper side with mesh wire fabric 65, for a purpose which will hereinafter be apparent.

The wheels 7 and 8 are provided with pneumatic tires. The wheels 7 are journaled on the ends of an axle 66 and are disposed outwardly of the side portions 15 and 16, as seen in FIGS. 3 and 4. The axle 66 is secured across the under side of the bottom 11 near the rear wall 14.

A gooseneck 67 is secured to the outer sides of the bottom 11 and front wall 13 and has an upper portion 68 projecting forwardly from the front wall. A wheel fork 69 is disposed beneath the forward end of the portion 68 and has an upstanding post 70 which is turnably secured therein for swivelly mounting the fork. The wheel 8 is rotatably mounted in the fork 69 on an axle 71 which additionally provides a pivot for the forked end 72 of a handle 73, by means of which the dryer 5 is pulled and steered.

The gooseneck 67 is so constructed that the front end of the cabinet 6 is elevated slightly relative to the rear end thereof, so that the axis of the enclosure 31 is inclined slightly downwardly and rearwardly from its forward end which is located adjacent the front wall 13.

Assuming that the plug 60 is connected to an electric current source, the closure 17 can be opened for manually operating the switches 56, 57 and 58 for energizing the heating elements 53, 54 and 55 and the motor 47 for revolving the enclosure 31 and for drying the contents thereof. The dryer 5 may be used for example on an inclement day or a day when the ground is wet along the side line of a football field. As footballs are removed from play due to becoming wet, such footballs, not shown, may be dried with the dryer 5 rather than the moisture being wiped from the surface thereof with a towel, as is the conventional practice.

When the door 17 is opened and the switches manipulated to de-energize the motor 47 and heating elements, the handle 45 of the sliding closure 39 is grasped to move said closure from left to right from a closed position against the left hand end wall 36, FIG. 2, to an open position, to or beyond the position of said closure as seen in FIG. 2, so that one or more wet footballs, not shown, can be placed in the cage 35. This operation can be repeated intermittently as additional wet footballs are removed from the game. After each application of footballs to the cage 35, the closure 39 is returned to a closed position and the switches 56, 57 and 58 are manipulated for energizing the heating elements and motor. The door 17 is returned to a closed position

and the balls contained within the cage 35 are dried by the heating elements 53, 54 and 55 as the balls tumble within the cage 35 to expose all parts thereof to the heat. As there is no circulation of air within the cabinet 6 with doors 17 and 23 closed, the contents of the cage 35 will not stiffen when dried.

Due to the slight inclination of the enclosure 31, the balls therein while being tumbled will gradually move toward the right hand end thereof, so that additional 10 wet balls can be conveniently applied, as heretofore described. Additionally, when the switches are in an open position and the closure 17 is opened, the closure 40 can be moved to the right from its closed position of FIG. 2 for removing dried balls from the right hand end 15 of the cage 35, either to be returned to the playing field or to be stored on the pan 64. The mesh wire fabric liner 65 will prevent balls stored thereon from coming in contact with any moisture which may have dripped onto the upper portion of the pan 64 from the cage 35.

20 Thereafter, when a dry ball is needed, the closure 23 can be opened and a dry ball removed from the pan 64 through the opening in the rear wall thus provided, without interrupting rotation of the enclosure 31 or operation of the heating elements.

25 It will be readily apparent that the dryer 5 is equally well adapted for drying other types of athletic equipment including soccer balls, basketballs used for outdoor play, baseballs, baseball gloves and athletic shoes of all types.

30 It will also be apparent that various other types of heating elements may be substituted for the lamp bulbs and that the cabinet 6 can support a storage battery or an electric generator operated by a small gasoline engine to render the dryer completely self contained.

35 Various other modifications and changes are contemplated and may be resorted to without departing from the function or scope of the invention.

I claim as my invention:

40 1. A dryer for athletic equipment comprising a portable cabinet having an access door, an elongated cage of open work construction adapted to contain plural pieces of equipment to be dried and having a closure at one end affording access to the interior thereof when in an open position, means rotatably mounting said cage within the cabinet at a downward incline from said end, means for revolving the cage, heating means for drying the contents of the cage, said cage having closed ends and being of a size whereby equipment being dried will tumble toward and collect in the other lower end thereof, and a second closure located at said lower end and accessible through said door for removal of the dried equipment from said lower end of the cage.

45 2. A dryer as in claim 1, said cage having closed ends and including movable sections forming said closures, and means mounting said closures for sliding movement longitudinally of the cage between open and closed positions.

50 3. A dryer as in claim 1, a tricycle type mount providing the mobile support for the cabinet including a pair of transversely spaced rear wheels and a front steering wheel, and a handle connected to the front steering wheel for propelling and steering the dryer.

55 4. A dryer as in claim 1, said means for revolving the cage comprising an electric motor, said heating means comprising a plurality of banks of heat lamps disposed around and spaced from the cage, and electric switches carried by the cabinet and connected to an electric cur-

rent source for controlling operation of the electric motor and lamp bulbs.

5. A dryer as in claim 1, a pan disposed in the bottom of the cabinet for catching any moisture dropping from the cage, said pan being inclined in the same direction as the cage.

6. A dryer as in claim 5, said pan being adapted to support dried equipment stored in the cabinet, and means lining the upper surface of the pan to support the equipment stored thereon out of contact with any 10

moisture in the pan.

7. A dryer as in claim 6, said cabinet having a second door opening into the cabinet beneath the lower end of the cage and affording access to the cabinet for removal of dried equipment from the pan without interrupting operation of the cage or the heating means.

8. A dryer as in claim 1, said cabinet being lined with a heat insulating material.
